Primary Examiner — Keli L Hill(74) *Attorney, Agent, or Firm* — Volpe Koenig(57) **CLAIM**

The ornamental design for fluid distribution equipment, as shown and described.

DESCRIPTION

FIG. 1 is a top plan view of fluid distribution equipment in accordance with my design;

FIG. 2 is a top, front perspective view thereof;

FIG. 3 is a bottom plan view thereof;

FIG. 4 is a bottom, rear perspective view thereof;

FIG. 5 is a front elevational view thereof;

FIG. 6 is a rear elevational view thereof;

FIG. 7 is a left side elevational view thereof; and,

FIG. 8 is a right side elevational view thereof.

The broken lines represent portions of the fluid distribution equipment that form no part of the claimed design.

1 Claim, 8 Drawing Sheets(56)
